UNITED STATES PATENT OFFICE.

JAMES LYLE GLENN, JR., OF CLARKSVILLE, TENNESSEE.

DESIGN FOR A LACING-STUD.

SPECIFICATION forming part of Design No. 29,668, dated November 15, 1898.

Application filed October 21, 1898. Serial No. 694,235. Term of patent 14 years.

To all whom it may concern:

Be it known that I, JAMES LYLE GLENN, Jr., a citizen of the United States, residing at Clarksville, in the county of Montgomery and State of Tennessee, have invented and produced a new and original Design for Lacing-Studs; and I do declare the following to be a full, clear, and exact description of the same.

The characteristic features of the present design for a lacing-stud may be enumerated as follows: a flat base of substantially egg-shaped general outline, a comparatively short tubular shank on the under side of said base and centrally located, a rounded post rising from the base at the front of the same, and a broadening arch extending from the top of said post over to the back part of the base, said base, post, and arch bounding an opening transverse to the tubular shank.

The drawings which accompany and form part of this specification illustrate, on a greatly-enlarged scale, a lacing-stud of the design herein claimed.

Figure 1 of said drawings represents the stud in perspective, Figs. 2 and 3 representing the same in cross-section at right angles, and Fig. 4 representing the stud in plan.

In the drawings the reference-letter *a* designates the base-plate, of general egg-shaped outline, and *b* the short tubular shank springing from the under side of said base-plate centrally thereof, the latter projecting outwardly beyond or overhanging said shank on all sides and this shank being beveled on the outside all around its lower edge. A rounded

post *c* springs from the upper side of the base-plate, at the narrower end thereof, which is the front, the forward side of such post merging into the front edge of the plate and the base of the post widening so as to merge 40 into the top face of the base-plate. An arch *d* extends backwardly from the top of such post and downwardly to the rear portion of the base-plate, such arch being somewhat flattened and widening gradually as it extends rearwardly and then more pronouncedly as it curves downwardly, as shown at *d'*. The rear leg *d''* of the arch has a transverse curvature corresponding with the curvature of the rear edge of the base-plate, so as to 45 practically merge into the same, and its end edges *d²* are slightly concave, the base of the leg being widened somewhat. The rear portion of the arch has an interior longitudinal curvature, and this curvature of the arch 50 continues throughout its top part and merges into the inner surface of the post *c*. The side edges of the arch are rounded throughout and merge into the side surfaces of the post. 60

What I claim is—

The design for a lacing-stud substantially as herein shown and described.

In testimony whereof I affix my signature in presence of two witnesses.

JAMES LYLE GLENN, JR.
